UNITED STATES PATENT OFFICE

1,975,157

COUNTER

Fred W. Kraft, Oak Park, Ill., assignor to Reflector Hardware Corporation, Chicago, Ill., a corporation of Illinois

Application April 20, 1934, Serial No. 721,449

12 Claims. (Cl. 45—141)

This invention relates to counters and its principal object is to provide a counter with a rail or rail attachment having aligned spaced sockets or openings disposed along the length of the rail and adapted to receive and hold in alignment the stems of price card holders, display racks, brackets and other fixtures or display carrying members.

The common practice at present is to provide stands for carrying the price cards, racks, brackets or other display devices, and these stands are placed promiscuously on the counter, among the goods displayed. This not only detracts from the appearance of the merchandise displayed, but the stands are often knocked down, misplaced and scattered promiscuously about the merchandise.

One object is to provide a rail as a part of the counter or an attachment to the usual rail, formed with spaced aligned sockets or apertures into which are inserted the stems of the fixtures for supporting the cards or articles displayed, thus aligning all of the stems along an edge of the counter and presenting a neat, pleasing and symmetrical appearance, and at the same time minimizing the likelihood of the display devices being knocked down.

With these and other objects and advantages in view, this invention consists in a counter having a rail provided with aligned sockets or apertures for receiving and holding in alignment a plurality of display carrying stems. The invention further consists in the provision of the aligned sockets or apertures in the back rail itself or in an attachment secured to the counter. The invention further consists in the several novel features of construction, arrangement and combination of parts hereinafter fully set forth and claimed.

The invention is clearly illustrated in the drawings accompanying this specification, in which: Fig. 1 is a perspective view of a counter exemplifying one form of the present invention;

Fig. 2 is a detail perspective view of a fragment of the counter on an enlarged scale;

Fig. 3 is a detail fragmental plan of the counter on an enlarged scale;

Fig. 4 is a detail vertical cross-section taken on the line 4—4 of Fig. 3;

Fig. 5 is a fragmental plan illustrating a modified form of the invention, and

Fig. 6 is a vertical cross-section taken on the line 6—6 of Fig. 5.

Referring to said drawings and first to Figs. 1 to 4 inclusive, the reference character 10 designates the top of a counter, table or the like A, and 11, designates a rail, here shown as the back rail

of the counter. The rail projects above the counter top two or three inches and serves, in one capacity, to retain the merchandise on the counter.

In accordance with one form of the invention, a series of aligned sockets are provided in the rail along its length, adapted to receive the stems 13 of fixtures or display carrying members and hold them in alignment along the edge of the counter. The display carrying members may take various forms, such as are adapted for displaying price cards, merchandise and other articles.

In the particular form of the invention illustrated in Figs. 1 to 4, inclusive, the back rail is formed of sheet metal and extends along the entire length of the counter or along so much thereof as is desirable. Usually the rail is of a deep channel shape, one of the sides 14 thereof being bent outward laterally adjacent its lower edge to form a flange 15 that is adapted to be fastened to the counter top 10 by screws 16. The other side 17 of the rail projects down below the side 14 so as to extend along the rear edge of the counter top. A bent up channel shaped strip 18 extends between the two sides 14, 17, and is welded or otherwise secured thereto. The strip 18 lies under the flange 15, is bent up along the inner face of the side 14, then bent horizontally to form a web 19 spanning the space between the two sides 14, 17, and then bent down along the inner face of the side 17. The strip 18 serves to brace the two sides 14, 17 apart and also serves to receive the ends of the stems as will appear presently. Screws 23 fasten the two strips to the rear edge of the counter top.

The upper edge 20 of the rail and the web 19, are each formed with a series of spaced apertures designated by the character 21, 22, those in the edge 20 being in vertical alignment with those in the web 19 and both series of apertures being arranged in alignment along the length of the rail. The vertically aligned apertures provide sockets for receiving the stems 13 of the fixtures or display carriers, two of which are shown at B. The display carriers may take various forms, as for instance for displaying price cards, merchandise and other articles. The apertures being arranged in alignment, the stems of the display carriers are held in alignment along one edge of the counter. Sometimes flat bar stems are used for the display carriers and one such flat stem is shown at 13^a. The apertures are mainly round to receive round stems, and desirably notches 24 are provided at diametrically opposite places at

110

the edge of each round aperture to provide a wide slot to recover the flat stems. The flat stems may be twisted very slightly to provide a spring tension against the edges of the notches and thereby prevent any looseness between the rail and flat stems.

To support and hold the round stems from turning in the apertures, a lengthwise extending groove 25 is formed in the top edge of the rail and the round stems are provided with pins or lugs 26 that project laterally therefrom and seat in the groove. The pins or lugs also support the stems upon the rail. The groove may be formed by depressing the metal of the top edge of the rail along the medium line thereof.

The apertures are spaced fairly close to each other which permits the display carriers to be placed approximately at any point along the length of the rail, which is of importance as it permits the display carriers to be placed symmetrically behind the goods displayed on the counter.

It is to be observed that the rail serves two purposes, namely it provides an upstanding shoulder or rim at the edge of the counter for preventing articles from falling off the counter, and it provides the support for holding the display carrying stems in alignment at the edge of the counter.

In the modified form illustrated in Figs. 5 and 30, the counter top 10^a is provided with the usual back rail 12. A separate channel shaped strip 11^a, desirably formed of sheet metal is provided for holding the display carrying stems. The upper and lower flanges or webs of the strip 11^a are provided with apertures 21^a, 22^a as in the preferred form for the reception of the stems 13, 13^a, and the upper edge of the strip is grooved to receive the pins or lugs of the stems to support and hold the round stems against turning. The strip is secured to the rail by screws 23^a.

In order that the weight of the fixtures or display carriers may be carried by the counter top rather than by the back rail, brackets 26 may be provided on the underside of the table top and fastened thereto by bolts and nuts 27. The brackets are suitably spaced along the length of the counter and project beyond the rear edge thereof where they are formed with bosses 28 that engage the underside of the channel strip 11^a and support the same and the fixtures carried thereby. An upstanding pin 29 projects from the lug of each bracket and extends through two vertically aligned apertures in the channel strip. The pins 29 prevent the channel strip from tilting, thereby enabling the strip to hold the fixtures in upright position with all of the stems in alignment.

I claim as new and desire to secure by Letters Patent:

60. 1. A counter having a back rail provided with a series of spaced, horizontally aligned sockets along its length, and unconnected display carrying stems insertable into any selected sockets and held in alignment by said sockets, there being co-acting means on the rail and stems to hold the latter against rotation.

70. 2. A counter having a back rail formed with upper and lower webs having series of horizontally and vertically aligned spaced apertures, and display carrying stems insertable into any selected aligned upper and lower apertures and held thereby in alignment with each other.

75. 3. A counter having a back rail provided with a flanged strip on its rear side formed with upper and lower horizontally and vertically aligned

apertures disposed along its length, and display carrying stems insertable into selected vertically aligned apertures and held thereby in alignment with each other.

4. In a counter, a back rail, formed of sheet metal, secured thereto, the back rail having upper and lower webs each formed with spaced apertures along its length, the apertures in the two webs being in vertical alignment, and adapted to receive and hold stems of display carriers.

5. In a counter, a back rail, formed of sheet metal, secured thereto, the back rail having upper and lower webs, each formed with spaced apertures arranged in vertical alignment and the upper web having a lengthwise extending depression substantially as and for the purpose set forth.

6. In a counter, a back rail composed of two channel shaped strips, one within the other and providing upper and lower webs, there being vertically aligned apertures in said webs adapted to receive the stems of display carriers.

7. In a counter, a counter top, a back rail secured thereto, a channel shaped strip arranged along the rear side thereof, said strip being provided with a series of apertures in its upper and lower flanges, and a bracket secured to the underside of the counter top and projecting under the channel shaped strip, said bracket having a lug for supporting the strip, and an upstanding pin engaging in vertically aligned apertures in the strip.

8. In a counter, a back rail strip having upper and lower webs formed with vertically aligned round apertures from the edges of which extend aligned notches, substantially as and for the purpose set forth.

9. In a counter, the combination of a counter top having a rail along one edge thereof provided with a series of aligned sockets along its length and having a lengthwise extending groove along its upper edge, and display carrying stems insertable into said sockets, said stems having transversely extending projections adapted to seat in said groove.

10. In a counter, the combination of a counter top, having a metal strip secured along one edge thereof and formed with upper and lower webs, and the upper web having a longitudinally extending groove therein, there being series of vertically and horizontally aligned apertures in the webs, and display carrying stems insertable into said vertically aligned apertures, said stems having transversely extending projections adapted to seat in said groove.

11. In a counter, the combination of a counter top having a metal strip secured along one edge thereof and formed with upper and lower webs, there being series of vertically and horizontally aligned apertures in said webs, and display carrying stems insertable into the vertically aligned apertures, said stems having lateral projections arranged to rest upon one of the webs.

12. In a counter, the combination of a counter top having a rail along an edge, a channel shaped strip secured to one side of said rail, said strip having a groove in its upper web extending longitudinally thereof, and vertically and horizontally aligned apertures in the upper and lower webs, and display carrying stems insertable into the vertically aligned apertures, said stems having transversely extending projections adapted to seat in said groove.

FRED W. KRAFT.
